THEODORE PICKERING, OF BATAVIA, NEW YORK, ASSIGNOR TO DOEHLER DIE-CASTING CO., A CORPORATION OF NEW YORK

CORE FOR UNDERCUT CUP-SHAPED ARTICLES

Application filed August 28, 1929. Serial No. 388,903.

My invention has particular reference to the problems arising in the casting of cup-shape articles in permanent molds where the article has an internal undercut.

5 Sand or other disintegrable cores have been used for the purpose, and in some instances permanent collapsible cores have been used. A permanent core is obviously more desirable for several reasons, among 10 which are economy and a resultant smoother surface to the casting formed by the core. However, the production of collapsible cores requires an accuracy of machining and truing of parts which render such cores relatively expensive; and moreover the labor of drawing and again assembling such cores is considerable as compared with solid cores.

In particular is this true of cup-shape articles where the internal walls are cylindrical and have overhanging portions. For 20 example, pistons for internal combustion engines present an especial problem by reason of the complex internal shape due to the presence of the wrist-pin bosses.

25 In accordance with my invention I take care of the undercuts formed by the bosses by the use of disintegrable core sections and I use a solid permanent core section for all the rest of the casting, the sections being 30 united with sufficient permanency to withstand the casting pressure, and yet being easily separable after the casting operation. The permanent part constitutes the entire core of the skirt of the piston outside of the 35 transverse plane containing the diameters of the wrist-pin bosses, and the central portion of the remainder. That portion of the permanent part of the core which extends beyond the wrist-pin bosses, constitutes a reduced axial extension transverse to the wrist-pin bosses. This extension, the sides of 40 which converge, extends to the end of the core or the inner surface of the head of the piston. On either side of the extension 45 of the permanent core and secured thereto there are disintegrable sand portions having a shape complementary to the undercut portion of the article. Thus, when the casting 50 is completed, the permanent portion of

the core may be withdrawn and the sand portions may be loosened and removed.

I shall now describe one embodiment of my invention in connection with the accompanying drawings in which:

Fig. 1 is a perspective of a core embodying my invention;

Fig. 2 is a section of an internal combustion engine piston with a core placed therein; and

Fig. 3 is a transverse section taken on the line 3—3 of Figure 2.

The core illustrated in the drawings, which is the type used in casting pistons for internal combustion engines, is adapted to be used with a permanent mold such, for example, as are used in die casting and which are well known to those skilled in the art. Essentially, the core consists of three parts, namely, a central permanent part 1 and two disintegrable parts 2.

The permanent part 1 of the core is adapted to fill the interior of the piston outside the transverse plane containing the diameters of the wrist-pin bosses 3 of the piston. The outer surface of the part 1 is, therefore, complementary to the desired contour of the inner surface of the piston outside the transverse plane containing the center lines of the wrist-pin bosses 3. An axial extension 4, transverse to the bosses 3 and having converging sides, extends from the lower end of the permanent part 1 and is integral therewith. The flange 4 extends along the inside of the piston to the head thereof; along that portion of the piston which does not contain undercut recesses. The converging sides of the flange 4 are provided with undercut or dove-tail tongues 5 which are received in complementary grooves in the parts 2 to unite the three parts of the core. This construction is not, however, essential, as the converging sides of the flange 4 may be smooth and the parts 2 glued or otherwise secured thereto.

The parts 2 may be constructed from plaster of Paris or sand with which a binding agent has been mixed. The parts 2 extend from the center of the wrist-pin bosses 3, to the head of the piston as shown. Be-

low the recesses in the parts 2 which are provided for forming the wrist-pin bosses, there are provided projections 6 which are adapted to form the undercut recesses of the piston. These recesses, below the bosses, are necessary to properly proportion the metal in the piston. A diametrical groove is provided in the lower edge of the completed core and extends up the sides of the parts 2 to the lower surface of the wrist-pin bosses 3. The groove is adapted to form a reinforcing flange 7 across the head of the piston. It is to be noted that the parts 2 are identical and therefore a single pattern may be used for making them.

The complete core is placed in the permanent mold and held in place by the wrist-pin cores. The molten metal is then forced in around the core. After the metal has cooled sufficiently the permanent part 1 of the core may be removed. The piston or other article is then subjected to a heat treatment which, incidentally, destroys the binding material in the sand molds and after which they may be jarred loose from the casting.

It will be evident to those skilled in the art that I have devised a simplified core for undercut cup-shape articles which considerably reduces the time required for making up such cores.

It is obvious that various changes may be made by those skilled in the art in the illustrated embodiment of my invention above particularly described within the principle and scope of my invention as expressed in the appended claims.

I claim:

1. A core for cup-shape articles having an internal undercut comprising a permanent central section and two disintegrable side sections, the central section comprising the entire core outside the undercut portions of the casting and the central part of the core at the undercut portions of the casting.

2. A core for cup-shape articles having an internal undercut comprising a permanent section forming the entire core outside the undercut portion of the article and having a reduced axial extension forming the central part of the core at the undercut portion of the article and two disintegrable core sections having a shape complementary to the undercut portion of the article and detachably secured to the axial extension on said first section.

3. A core for cup-shape articles having an internal undercut comprising a permanent section forming the entire core above the undercut portion of the article and having a longitudinal extension forming the central part of the remainder of the core, and two disintegrable sections for forming the undercut recesses in the article detachably secured to the extension on said permanent

section, the contiguous faces of the sections having dove-tail interlocking relation.

In witness whereof, I hereunto subscribe my signature.

THEODORE PICKERING.
